CLAIM

The ornamental design for a panty liner, as shown and described.

DESCRIPTION

FIG. 1 is a top plan view of a panty liner according to the present invention; and,

FIG. 2 is a bottom plan view of the panty liner according to the present invention.

The panty liner according to the present invention is flat, thus sides of the article do not contain any ornamentation and therefore have not been depicted herein.

The broken lines depict portions of the panty liner that form no part of the claimed design.
